(57) **CLAIM**

The ornamental design for a golf club shaft, as shown and described.

DESCRIPTION

FIG. 1 is a front view of a golf club shaft showing our new design;

FIG. 2 is an enlarged perspective view of the portion circled in FIG. 1; and,

FIG. 3 is an end view thereof.

The broken lines are environmental only and form no part of the claimed design. The ends of the shaft in FIGS. 1 & 2 indicate indeterminate length.
